UNITED STATES PATENT OFFICE.

WALTER ZETZMAN, OF CORNELIUS, OREGON.

HOISTING AND CONVEYING APPARATUS.

1,248,980.

Specification of Letters Patent.

Patented Dec. 4, 1917.

Application filed May 15, 1917. Serial No. 168,882.

To all whom it may concern:

Be it known that I, WALTER ZETZMAN, a citizen of the United States, and a resident of Cornelius, in the county of Washington and State of Oregon, have invented a certain new and useful Improvement in Hoisting and Conveying Apparatus, of which the following is a specification.

The present invention relates to hoisting and conveying apparatus, and has particular reference to a device adapted for use in barns, stables, and the like, for transporting and distributing feed, hay, and other material to feed boxes, and other parts of the building, and for various other uses.

An object of the present invention is to provide a device of this character which is so constructed as to support a carrier box, and provide for the adjustment of the same in the various horizontal angles beneath the carriage of the device.

The invention also embraces novel means for raising and lowering the carrier and retaining the same in elevated position while being conveyed.

The above, and various other objects and advantages of this invention will be in part described and in part understood, from the following detailed description of the present preferred embodiment, the same being illustrated in the accompanying drawing, wherein:

Figure 1 is a side elevation of a hoisting and conveying apparatus constructed according to the present invention.

Fig. 2 is an end elevation of the apparatus in raised position.

Fig. 3 is a detail enlarged section taken longitudinally and substantially centrally through the carrier and the parts directly mounted thereon.

Fig. 4 is a transverse section taken substantially centrally through the same.

Referring to these drawings, wherein like parts are designated by similar characters of reference throughout the several views, 10 designates a double rail track, supported in any convenient manner upon hangers 11 which are adapted for securing to the rafters, or other portions of a building in which the apparatus is adapted to be employed.

A carriage 12 of hollow construction provided with outstanding web portions at its opposite ends carries upon said ends a pair of upstanding parts or brackets 13 upon

the upper arms of which are pivotally mounted rollers 14 for engagement with the opposed rails of the track 10. The carriage 12 is preferably open at the opposite ends 60 and provided intermediate its ends with a downwardly extending hub portion 15 through which is vertically movable a pin 16 constituting a trip and bearing at its lower end against a pair of inwardly extending lugs formed upon the upper pivoted ends of the grip or jaw members 17, the latter being mounted upon pins 18 carried upon the lower end of the hub 15.

A horizontally swinging frame 19 is supported upon and arranged beneath the carrier 12, the same being substantially U-shaped in cross section, and connected to carrier 12 by a tubular bolt or connecting member 20. The member 20 is provided at its 75 upper end with an outstanding annular flange, and passes downwardly through openings formed in the adjacent abutting faces of the carriage 12 and the frame 19. Anti-friction bearings 21 are interposed between the lower face of the flange of said member 20, and the upper face of the bottom of the carriage 12. The lower end of the tubular member 20 is externally threaded and is provided with a pair of interlocking nuts 85 or rings 21, the upper one of which is adapted to engage the lower face of the top wall of the frame 19. The jaws or grip members 17 are relatively long and project downwardly through the tubular member 20, and 90 into the frame 19. The frame 19 is thus mounted on the lower end of the tubular member 20, and the latter is freely rotatable in the carriage 12 by the provision of the ball bearings as shown. It will be noted 95 that the carriage 12 is provided with overhanging web portions at its opposite ends formed by cutting away the sides to admit the uninterrupted turning of the frame 19 beneath the carriage.

The frame 19 is formed at opposite ends with bracket portions 22 in which are mounted for free rotation peripherally grooved rollers 23, and one of the brackets is provided with a pair of spaced-apart outstanding arms 24 between the outer ends of which is mounted a drum 25. The drum 25 is keyed upon a shaft 26 which projects at one end beyond the adjacent bracket arm 24, and which is provided with a sprocket 110 wheel 27 over which is trained an operating chain 28.

A fall block 29 is arranged beneath the frame 19, and is provided therein with a pair of grooved pulleys 30 adapted to receive thereunder portions of a fall rope 31 which pass through the lower end of the block 29. One end of the fall rope 31 is secured, as at 32, to the frame 19 at one end of the frame, said end of the fall rope 31 passing through the block 29 and upwardly over the opposite roller 23, then 5 downwardly from said roller through the block 29 and over the roller 23 at the first end of said frame 19. The free end of the fall rope 31 passes from the pulley 23 to the drum 25, is secured at one 10 end thereto and is wound to some extent thereabout. When the drum 25 is rotated, it is evident that the fall rope 31 will be drawn over the pulley 23 and through the block 29 to raise the latter. The block 29 is provided with an upstanding bail 33, having 15 a shouldered head 34 adapted for engagement between the lower beveled ends of the jaws 17. The jaws 17 are adapted to swing inwardly toward each other by gravity, and to engage beneath the shoulder of the head 34, thus retaining the fall block 20 in raised position beneath the frame 19.

A clevis 35 is pivotally and swivelly mounted upon the lower end of the fall block 29, and is connected, by means of a swivel eye 36 to an outstanding strap or bail 37 carried upon a carrier box or other receptacle 38. The box 38 is elongated, is open 30 at one end, and is held from tilting by the provision of a strap 39 which is secured to the closed end of the box 38, and which extends to the clevis 35.

The track 10 is provided with a tripping block 40 at any suitable point which lies in 40 the path of the tripping pin 16 and is adapted to depress the latter upon the movement of the carriage 12 over the track 10.

In operation, when the carrier 38 is lowered, the same may be filled to the desired 45 extent with feed or other material to be distributed and conveyed, and the hand chain 28 is then actuated to rotate the drum 25 and wind the fall rope 31 over the same. As the fall rope 31 is wound upon the drum, 50 the fall block 29 is raised in a position beneath the frame 19, and when drawn into its uppermost position, the head 34 of the fall block engages with the jaws 17, setting the same apart, and the jaws interlock with 55 the head to hold the fall block in raised position. The carrier 12 may now be actuated either by gravity, or otherwise, to travel over the track 10 to the desired point 60 of distribution. When the carrier reaches the point of distribution, at which point, the tripping block 40 is located, the block 40 strikes the pin 16 and depresses the same to spread apart the jaws 17 and thus release 65 the fall block 29. The fall block 29 being

thus released, is drawn downwardly by the weight of the material within the carrier box 38. The fall rope 31 may be so adjusted as to limit the downward movement of the carrier 38. The hand chain 28 may 70 also be actuated and controlled for lowering the box 38 to the desired position. A rake or other suitable device may be employed for withdrawing the contents of the box 38 when the latter is adjusted to the desired 75 position with respect to feed boxes and the like.

It will be particularly noted that the frame 19 may be turned through substantially any angle about the carriage 12 so as 80 to dispose the hand operating chain 28 in any desired position, and the carrier 38, by virtue of its swivel connection with the fall block 29, may be turned to present its open end at any desired side of the apparatus. 85

It will also be noted that the apparatus comprises but relatively few parts, no springs are employed, and the means for locking the fall block 29 in raised position 90 is automatic, and positive.

It is to be understood that various changes and modifications may be made in the details of construction of the above specifically described hoisting and conveying apparatus, without departing from the spirit 95 of the invention, and being restricted only by the scope of the following claims.

I claim:—

1. In hoisting and conveying apparatus, the combination of a carriage, a pin movable in the carriage, a pair of jaws suspended from the carriage and having portions engaging beneath the pin for supporting the same, a frame arranged beneath the casing, a fall rope in the frame, and a fall block mounted on the fall rope and adapted to be raised thereby into interlocking engagement with said jaws, said pin being adapted to be depressed to spread said jaws and release the fall block. 100

2. In hoisting and conveying apparatus, the combination of a carriage, a pin movable in the carriage, a pair of jaws suspended from the carriage and having portions engaging beneath the pin for supporting the same, a frame arranged beneath the carriage, a tubular member connecting the frame to the carriage and surrounding the jaws to retain the same from spreading beyond a predetermined limit and releasing 115 the pin, a fall rope in the frame, and a fall block mounted on the fall rope and adapted to be raised thereby into interlocking engagement with said jaws, said pin being adapted to be depressed to spread said jaws 120 and release the fall block.

3. In hoisting and conveying apparatus, the combination with a track, and an abutment on the track, of a carriage on the track, a fall rope supported by the carriage, 130

- a fall block mounted on the rope and having a shouldered head, a pair of jaws pivoted in the carriage and adapted to engage beneath the head to support the fall block, and a pin 5
5 slideable through the carriage and engaging said jaws, the pin being adapted to strike said abutment and to be depressed thereby for swinging said jaws from said head to release the fall block.
- 10 4. In an apparatus as specified, the combination of a carriage provided with a central hub portion, a pin vertically movable in said hub portion, a pair of suspended jaws mounted upon the lower end of the hub portion, and having inwardly extending lugs 15 for engagement with said pin to support the same, a frame arranged beneath the carriage, a tubular member extending through the frame and the carriage about said jaws, 20 means for securing said tubular member in position to pivotally connect and suspend the frame, a fall block arranged beneath the frame, and a fall rope carried upon the frame for raising said block into engagement with said jaws, said pin being adapted 25 to be depressed to spread said jaws and release the fall block.
5. In apparatus as specified, the combination of an open carriage, a frame arranged 30 beneath the carriage, a tubular member engaging through the carriage and frame to connect the same, a pair of jaws mounted upon the carriage and depending through said tubular member into the frame, a pin 35 vertically movable in the carriage, and engaging said jaws, said pin being adapted to be depressed to spread said jaws, a fall block, a fall rope mounted in the frame and engaging said fall block to raise the same 40 into engagement with said jaws for inter-

locking engagement therewith, and hand controlled means carried by the frame and engaging said fall rope to actuate the same.

6. In hoisting and conveying apparatus, the combination of a carriage, a frame pivoted to the under side of the carriage and adapted to turn on a vertical axis, a fall rope in the frame, a fall block on the rope adapted to be raised into the frame and to turn therewith and provided with an upstanding head having an exterior annular shoulder, a pair of jaws pivoted in the carriage and depending into the frame for engagement with said annular shoulder to support the fall block and admit of the free 45 turning of the same, and a pin slideable upon the carriage and engaging said jaws and adapted to be depressed for spreading the jaws out of engagement with the shoulder on the fall block to release the latter. 50

7. In hoisting and conveying apparatus, the combination with a track, and an abutment on the track, of a carriage on the track, a frame pivoted to the under side of the carriage and adapted to swing thereon about a vertical axis, a fall rope in the frame, a fall block mounted on the fall rope, said fall block being provided with an upstanding head having an annular shoulder, a pair of jaws pivoted in the carriage and depending into the frame, and adapted for engagement 55 with the shoulder of the fall block to support the latter in the frame and admit of the free turning of the frame and the fall block, and a pin slidably mounted in the carriage 60 and resting upon said jaws and adapted to engage said abutment and be depressed thereby for spreading the jaws from engagement with said shoulder. 65

WALTER ZETZMAN.
